CLAIM

The ornamental design for a floor stand for a phototherapy device, as shown and described.

DESCRIPTION

FIG. 1 is a front perspective view of a floor stand for a phototherapy device, showing our new design in a first condition of use;

FIG. 2 is front elevation view thereof;

FIG. 3 is rear elevation view thereof;

FIG. 4 is a right side elevation view thereof;

FIG. 5 is a right side elevation view thereof;

FIG. 6 is a top plan view thereof;

FIG. 7 is a front perspective view of the floor stand for a phototherapy device, shown in a second condition of use for clarity of disclosure;

FIG. 8 is front elevation view thereof;

FIG. 9 is a rear elevation view thereof;

FIG. 10 is a right side elevation view thereof;

FIG. 11 is a right side elevation view thereof; and,

FIG. 12 is a top plan view thereof.

The broken lines in the drawings depict environmental structure that form no part of the claimed design.

1 Claim, 12 Drawing Sheets
